UNITED STATES PATENT OFFICE.

JAMES LOUGHridge, OF PITTSBURG, PENNSYLVANIA.

IMPROVED WHITEWASH-BRUSH.

Specification forming part of Letters Patent No. **38,051**, dated March 31, 1863.

To all whom it may concern:

Be it known that I, JAMES LOUGHridge, of Pittsburg, in the county of Allegheny and State of Pennsylvania, have invented a new and useful Improvement in Whitewash-Brushes; and I do hereby declare the following to be a full, clear, and exact description thereof, reference being had to the accompanying drawings, forming part of this specification, in which—

Figure 1 is a perspective representation of the metallic frame or stock for holding the bristles forming the brush. Fig. 2 is a representation of the socket for receiving the handle of the brush. Fig. 3 is a representation of the cap-piece, which fits into the upper side of the metallic bristle-frame. Fig. 4 represents a finished brush constructed with my improvements. Fig. 5 is a brace for strengthening the metallic frame or stock.

In the several figures like letters of reference denote similar parts.

My improvement is applicable especially to brushes which are long and narrow, and in which it is important to have the bristles placed as close together as possible, such as are ordinarily used for whitewashing and similar purposes.

In round brushes—such as are ordinarily used for painting—the bristles are placed close together, but their form enables them to be readily secured by binding them with cord tightly round the handle, or by a wire ferrule. This is done by placing the bristles within the wire ferrule, previously prepared for that purpose, and then tightening them by forcing the tapered handle into place through the bristles in the ferrule. No such method of securing the bristles can be adopted in the manufacture of long, narrow brushes, which are ordinarily made either by tying the bristles in small bunches, ranged side by side on either side of a wedge-shaped piece of wood or stock, to which they are fastened by sewing them to the stock with cord passed through holes bored in the stock for that purpose, or the bristles are placed around the stock without being tied in bundles, and secured in place by nailing a strip of leather around the stock over the butt-end of the bristles. Both of these methods, however, cause a separation of the bristles on either side of the stock, which is very injurious to the operation of the brush, as it makes the brush leak—that is, the white-

wash runs down the bristles and collects in the space between them, near the stock, in such quantity as to cause it to run out. Another and serious objection to whitewash-brushes where the bristles are either sewed to the stock or nailed on with a leather band is that the bristles swell with the moisture when used, and the cord and leather, being both yielding when wet, allow of this expansion, but when the brush is dried again the bristles are found to be loose, and will come out, rendering the brush useless. In order to obviate these difficulties, I place the bristles side by side and close together in a long, narrow frame made of sheet-iron or other suitable material, braced by thin strips of the same material, which prevent the springing or opening of the frame without materially separating the bristles in the several compartments formed by these partitions.

Fig. 1 represents the metallic frame which composes the stock of the brush. It is made of two strips, *a a*, of sheet-iron or other suitable material, turned up at either end at right angles, so as to form the end of the brush. The ends *b b* thus turned up are lapped over each other and riveted together at *c*, forming a hollow frustum of a long, narrow wedge, as the sides are not placed parallel in their depth or width, although they are parallel in their length. As a frame or stock made of thin sheet metal of the shape described would be apt to open, so as to allow the bristles to fall out, it is strengthened and the sides confined by a number of braces, *d*, of the shape shown in Fig. 5, being that of a cross-section of the frame, but not so deep. These braces *d d* are made of thin metal, so as to separate the bristles as little as possible. Each end of the braces *d d* is turned up at right angles, as shown in Fig. 5, so that when the braces are placed in the frame the ends are parallel to the sides of the frame, to which they are fastened by rivets, as seen at *e e*, &c., Fig. 4. Thus these braces *d d*, being placed in the frame at short distances apart, form a number of compartments, narrower at the bottom than at the top, owing to the converging of the sides of the frame, as before described, and as seen in Fig. 1. The butts of the bristles being first saturated with cement, they are inserted into the frame, made as described, a sufficient quantity being put into each com-

partment to fill each as full as possible. The bristles are put in with their points downward from the upper or wider part of the frame, and are pulled downward, the greater thickness of the butt-end of the bristles and the cement on them preventing their passing the narrower, contracted part of the frame. When the cement dries, the bristles are firmly secured in their place; but to make them perfectly tight a little melted cement is poured over the ends of the bristles in the frame. This cement may be that ordinarily used for fastening the bristles in brushes. As the braces *d d* do not extend up to the top or upper end of the frame, there is a space left for the insertion of the cap-piece *f*, which is a strip of wood, long and narrow, and which fits into the top of the frame. The shape of this cap-piece *f* is shown in Fig. 3. It is fastened in place in the frame by a few screws or nails, *s s*, &c., (see Fig. 4,) screwed through the sides *a a* of the frame, near its upper edge.

A brush thus constructed can be made very cheaply, the bristles are much more firmly secured than by the old plan, and not being separated down the center by the stock nor tied in separate bundles, the brush is much better for use.

On the cap-piece *f* of the brush, midway from either end, is placed the socket for the handle. This socket is made of cast-iron, brass, or other suitable metal, and consists of a short cylinder, *g*, rising from a base or flange, *h*, by which it is screwed to the top of the brush.

In order to permit of the handle of the brush being inserted either straight or obliquely, I

use a socket of peculiar construction. (Shown in Fig. 2.) In addition to the cylinder *g*, which is at right angles to its base or flange *h*, I attach to the cylinder *g* another cylinder, *k*, at an acute angle—say about forty-five degrees—which opens into the upright cylinder *g*. These two cylinders *g* and *k* and the flange *h* are all cast in one piece. The use of this double socket is obvious. The handle of the brush may be inserted in either at pleasure, and may be conveniently removed from one to the other.

In order the more easily to secure the handle, a screw-thread may be cast or cut in the inside of the sockets *g* and *k*, so that the handle, being screwed in, will hold very firmly.

Having thus described my improvement in the mode of constructing brushes, what I claim as my invention, and desire to secure by Letters Patent, is—

1. The use, in the manufacture of brushes, of a prismoidal wedge-shaped frame made of thin sheet metal, and divided into compartments by partitions or braces, for the purpose of securing the bristles in a compact body, substantially as described.

2. In combination therewith, the use of a socket for the handle of brushes, consisting of two or more short cylinders cast in one piece, substantially as described.

In testimony whereof I, the said JAMES LOUGHridge, have hereunto set my hand.

JAMES LOUGHridge.
